United States Patent Office

Des. 190,991
Patented Aug. 1, 1961

190,991

MOTOR VEHICLE CAB

Theodore Ornas, Jr., Fort Wayne, Ind., assignor to International Harvester Company, Chicago, Ill., a corporation of New Jersey

Filed Oct. 21, 1960, Ser. No. 62,563

Term of patent 7 years

(Cl. D14—3)

FIGURE 1 is a perspective view of a motor vehicle cab embodying my new design;

FIGURE 2 is a side elevational view of the vehicle cab, and

FIGURE 3 is a front elevational view of the vehicle cab.

The portions shown in broken lines on the drawing are included for illustrative purposes only.

I claim:

The ornamental design for a motor vehicle cab, substantially as shown and described.
